THREAD REMOVER FOR WEFT REPLENISHING LOOMS

Albert Cederlund, Worcester, Mass., assignor to
 Crompton & Knowles Loom Works, Worcester,
 Mass., a corporation of Massachusetts

Application May 6, 1944, Serial No. 534,438

17 Claims. (Cl. 139—347)

This invention relates to thread removers for weft replenishing looms and it is the general object of the invention to provide means by which the thread extending from the thread holder to the selvage subsequent to a replenishing operation may be removed from the loom.

In the usual weft replenishing loom the reserve bobbins are held in a magazine and are transferred one by one into a shuttle on the lay under the magazine. Weft ends extending from the bobbins are held to a thread holder which projects outwardly from the magazine and serves as an anchorage for the threads of freshly transferred bobbins. This thread is eventually cut at the selvage and unless removed from the loom is likely to be drawn into the warp shed by the shuttle, or may fall on the weft detector or some other part of the loom and interfere with its proper operation. It is an important object of my present invention to provide a pair of gears which can be caused to rotate while in engagement with this thread and remove it from the loom.

The temple cutter does not ordinarily cut the thread at the selvage until several picks after transfer and if the control for the thread removing gears is initiated at the time of transfer some means must be provided for continuing the operation of the gears until after the thread is cut. It is another object of my present invention to provide means by which the normally stationary thread removing gears can start turning at the time of transfer and continue turning sufficiently long to remove the thread after it has been cut several picks subsequent to transfer.

It is a further object of my present invention to provide means for utilizing some of the energy of the transference arm to set a rotating member or flywheel in motion and utilize its rotation to control a thread remover. The rotating mass will continue to turn several picks after transfer and so long as its rate of turning is sufficiently high to keep centrifugal governors or the like in operative position the thread controller will be kept in operation.

In multicolor weft replenishing mechanisms it is possible for a second shuttle to be replenished a few picks after the first shuttle is replenished. The second shuttle will leave a second thread which will be cut subsequent to the cutting of the thread of the first shuttle and it is desirable that the mechanism be so constructed that it can remain in operation long enough to cut this second thread. If, for instance, there is a lapse of eight

picks between transfer and cutting and a second thread is left as the result of a transfer occurring four picks after the first transfer, this second thread will not be cut until twelve picks after the first transfer. In order to insure cutting of this second thread it is a further object of my invention to provide means by which each transfer starts a fresh cycle of operations which continues long enough to remove the corresponding thread.

5 10 In the form of the invention set forth hereinafter the rotating mass is given an impulse at each transfer whenever it occurs and regardless of previous transfers. By this arrangement it is possible to start a second period of operation 15 during the first period with assurance that the second period will last long enough to effect removal of the thread corresponding to it. This feature of my invention is not necessarily limited in its use to thread engaging gears.

20 It is a more particular object of my invention to utilize a pawl and ratchet mechanism to rotate the flywheel and hold the pawl away from the ratchet teeth after the driving impulse has been given to the wheel.

25 With these and other objects in view which will appear as the description proceeds, my invention resides in the combination and arrangement of parts hereinafter described and set forth.

In the accompanying drawings, wherein a convenient embodiment of my invention is set forth,

Fig. 1 is a front elevation of the replenishing end of a loom having my invention applied thereto,

Fig. 2 is an end elevation looking in the direction of arrow 2, Fig. 1,

Fig. 3 is an enlarged side elevation of the magazine looking in the direction of arrow 3, Fig. 1, parts being in section and the mechanism being shown in normal position,

Fig. 5 is an enlarged vertical section on line 5—5 of Fig. 3,

Fig. 6 is a horizontal section on line 6—6, Fig. 3,

45 Fig. 7 is an enlarged vertical section on line 7—7 of Fig. 4, showing the rotating member and the centrifugal switches in normal open position,

Fig. 8 is a vertical section on line 8—8 of Fig. 7,

50 Fig. 9 is a view similar to a portion of Fig. 7 but showing the switches closed due to rotation of the flywheel or rotating member in the direction of arrow a,

Fig. 10 is an enlarged side elevation of the bell 55 crank lever and connected parts shown in Fig. 3,

and showing the manner in which the pawl moves from normal to operating position relatively to the ratchet teeth, the ratchet wheel being in section,

Fig. 11 is an enlarged side elevation of the support for the rotating mechanism shown in Fig. 3.

Fig. 12 is a detail plan looking in the direction of arrow 12, Fig. 11, and

Fig. 13 is an enlarged detail side elevation of the thread holder looking in the direction of arrow 13, Fig. 1, and indicating diagrammatically the electric circuit which controls the electric motor which drives the thread gears.

Referring particularly to Figs. 1 and 2, I have shown a loom frame 20 which supports a lay 21 reciprocated backwardly and forwardly by the customary connectors 22. The lay has a shuttle box 23 which receives the shuttles of the loom one at a time, one of the shuttles being shown at S. Mounted in fixed position on the loom frame over the shuttle box is a magazine M which in the present instance is provided with four guideways I, II, III and IV for reserve bobbins. The bobbins in the guideways have weft ends W extending therefrom to a thread holder H mounted on an arm 24 secured at 25 to some part of the magazine, such as a tie rod 26 connecting the inner and outer end frames 27 and 28, respectively, of the magazine.

The loom has a breast beam 30 over which the fabric F extends and a temple cutter 31 is mounted on the breast beam close to the selvage of the fabric. When a weft replenishing operation occurs a reserve bobbin B moves downwardly to transfer position and is then inserted into the shuttle S by a transerrer arm 32 pivoted at 33 to the magazine foot 34 formed as part of end frame 27. A transfer latch 35 ordinarily in low inoperative position is raised to be engaged by a bunter 36 on the lay for the purpose of depressing the transerrer arm 32. Latch 35 is controlled by connections not shown from a top magazine shaft 37 to which is secured a casting 38 cooperating with bobbin releasers not shown.

When a bobbin is transferred its weft end moves away from the group of weft ends W and occupies a low position designated at T in Fig. 1. The shuttle is then picked to the opposite end of the loom and the thread T extends from the holder H to the fabric selvage. At some subsequent pick of the loom the temple cutter 31 severs this thread at the selvage and the thread may then fall either on the shuttle box in the path of the shuttle, or on some operating part of the loom, such as the weft detector indicated generally at D in Fig. 3 and located under the magazine. It is desirable that this thread be removed from the loom after it is cut at the selvage and it is the general purpose of my invention to provide mechanism by which this removal may be effected.

Referring particularly to Figs. 1, 2 and 13, the thread holder comprises front and back thread engaging gear members 40 and 41, respectively, which are rotatable on a support 42 forming part of the thread holder and secured to arm 24. These thread gears mesh with each other and during rotation exert a tensioning effect on the weft ends W which pass between them. In the present instance these gears are constructed to rotate by means of a motor 45, see Fig. 13, mounted on the support 42 and connected to a shaft 46 of one of the gear members. This motor is normally idle but when connected to a source

of electric energy as will be described hereinafter it turns the gears at a rate much faster than is usual for thread holders of this kind.

The mechanism for controlling the motor is mounted on a stand 50 the upper left corner of which, see Fig. 3, is secured to end frame 27 at 51, the upper right corner of which is bolted to frame 27 at 52, and the bottom of which is attached to frame 27 by screw 53. Projecting laterally from stand 50 are horizontally spaced vertical walls 54 which are connected by a bearing bridge 55 secured to them. The frame 50 and bridge 55 have aligning bearings 56 and 57, respectively, and frame 50 has projecting laterally therefrom a horizontal stud 58 on which is pivoted a lever 59 shown particularly in Fig. 10.

A shaft 60 is rotatable in the bearings 56 and 57 and has secured thereto a flywheel 61 the end of which adjacent to stand 50 has ratchet teeth 62 cut therein to form in effect a ratchet wheel integral with the flywheel. A pawl 63 is pivoted at 64 to the short arm 65 of lever 59, while the long horizontal arm 66 of lever 59 is forked and connected at 67 to a rod head 68. The bottom 20 of the latter, see Fig. 10, has a long shank 69 into which extends the upper end of a rod 70 slidably in the shank. The upper end of this rod has nuts 71 threaded thereon and a compression spring 72 is located between the nuts and shank 69, and a 30 collar 73 set on rod 70 normally engages the bottom of the shank.

The lower end of rod 70 has a rod head 74 connected at 74 to transerrer arm 32, and the latter, being normally raised, acts through collar 73 to hold lever 59 in the normal position thereof shown in Fig. 3. As shown in Fig. 6 the casting 38 has the intermediate part thereof adjacent to end frame 27 removed to make room for rod 70. Front and rear shelves 75 and 76, respectively, 40 cooperate with the usual bobbin releasers not shown and are connected by a bar 77 integral with them and parallel to shaft 37.

The flywheel 61 has mounted thereon two centrifugal levers 80 and 81 each pivoted to the flywheel at 82, see Fig. 7 on opposite sides of shaft 60. Each lever is provided with a weight 83 which tends during rotation of the flywheel to move outwardly away from shaft 60. Each of the levers 80 and 81 is provided with a hub 85 in which is secured a flat electric current conducting spring 86 extending away from the hub for engagement with a fixed pin 87 carried by the flywheel. Each of the springs may normally be straight as shown in Fig. 7 when the flywheel is at rest.

Shaft 60 has driven thereon an insulated bushing 90 on which is mounted a collector ring 91 insulated from the shaft 60 by the bushing and spaced from the flywheel by a flange 92 integral 60 with the bushing. A brush 93, having one end secured to a support 94 made of insulating material and attached to the rear wall 54, see Fig. 7, has its other end in continuous contact with the ring 91. A washer 95 made of insulating material 65 spaces ring 91 from outer bearing 57.

The circuit for the motor is shown diagrammatically in Fig. 13 and includes a source 96 of electric power one side of which is grounded by wire 97 and the other side of which is connected 70 by wire 98 to one side of the motor 45. The other side of the motor is connected by wire 99 to the brush 93 and ring 91. When the springs 86 contact the collector ring 91 the latter is grounded, indicated in Fig. 13 by wire 100, and the circuit 75 is closed to cause turning of the motor. Ordinarily

ily, however, this circuit is open and motor 45 and the gears 40 and 41 are stationary.

Under normal conditions the mechanism mounted on the bracket 50 is at rest, transerrer arm 32 and rod 70 are up, and arm 65 of lever 59 is in its left position. Arm 101 on the pawl is held against a stop pin 102 on stand 50 to keep the pawl away from the ratchet teeth, and spring 103 between finger 104 on the pawl and finger 105 on lever 59 is under tension. The spring contacts 86 are out of engagement with the ring 91 under these conditions due to their resilience and the fact that they engage pins 87. When a replenishing operation of the mechanism occurs latch 35 will be pushed forwardly by the lay-bunter 36 to lower the transerrer arm 32, and this is accompanied by downward movement of the rod 70. Spring 72 is strong enough to cause immediate rocking of lever 59 and cause pawl 63 to move from the full line position to the dotted line position, see Fig. 10. Because of the inertia of the flywheel spring 72 will then be compressed, and while its coils are closing the flywheel will start to turn due to engagement of the pawl with the ratchet teeth. As soon as spring 72 is completely closed the force of the transerrer arm will be transmitted positively to the flywheel, and the latter will turn in the direction of arrow *a*, Fig. 9. At the start of these operations the pawl moves away from pin 102 and is raised by spring 103 into engagement with one of the ratchet teeth.

As soon as the flywheel starts rotating the weights 83 move outwardly away from the shaft 60 and bend the springs 86 until the latter contact the ring 91 as shown in Fig. 9. At this time the previously described circuit shown in Fig. 13 is completed and the motor operates to turn the gears 40 and 41.

The transfer operation is completed when the lay reaches front center and as the lay recedes the arm 32 rises and collar 73 on rod 70 rocks lever 59 back to the normal position thereof shown in Fig. 3 with the pawl held out of engagement with the ratchet teeth by stop pin 102. Because of the energy stored in the flywheel the latter continues to turn for a few seconds during which time the contact springs 86 are held in contact with the ring 91. The motor is therefore continued in operation for a brief interval after transfer has been completed, and gears 40 and 41 are rotated at a relatively high rate of speed by the motor.

When the thread T is eventually cut at the selvage the flywheel will still be turning to keep the motor circuit closed and this circuit will remain closed by the continued turning of the flywheel long enough to enable the gears 40 and 41 to draw the thread T away from the selvage and eventually remove it from the loom. During this time the weft threads W are of course subject to the tension of gears 40 and 41 and any slackness occurring in the weft ends as the result of descent of the bobbins incident to transfer will be taken up. It is found that the single thread T, being free to respond to frictional engagement of the teeth of the thread gears, will be moved as already described even though the weft ends W are held by their bobbins against appreciable movement toward the gears.

It will be obvious that a second transfer can occur during the time that the flywheel is rotating. Should this happen the operation already described will be repeated and the pawl 63 will again impart a driving impulse to the flywheel. This second impulse gives the flywheel a fresh

start and causes it to continue turning for the period of its operation measured from the time of the second transfer. When the second thread is cut at the selvage, therefore, the flywheel will still be turning fast enough to maintain the motor in operation and continue its operation until the second thread is withdrawn from the loom.

While I have shown the spring 72 as a shock absorber, I do not wish necessarily to be limited to it, since it is possible to impart the force derived from the transerrer arm 32 directly to the flywheel at the very beginning of the down motion of the transerrer arm. The ratchet teeth are placed very close to the stand 50 to minimize any twisting which might result from the sudden application of force by the pawl. The shaft 60 is shown as rotatable in plain bearings 56 and 57, but it is obvious that I am not limited to this type of bearing.

From the foregoing it will be seen that I have provided simple means by which a force derived from the transerrer arm 32 is caused to set a flywheel in rotation and that this rotation effects closure of a centrifugal switch which in turn starts operation of a motor which operates thread removing mechanism. The parts are so designed that the flywheel continues to turn a sufficient period after cutting of the thread T at the selvage to insure removal of the thread from undesirable engagement with operating parts of the loom. It will also be seen that the fly-wheel is given an impulse each time the transerrer arm descends and it is for this reason that the motor will continue to run long enough to remove the thread remaining after any transfer, whether or not the flywheel is already turning due to a previous transfer. Furthermore, the pawl is held out of engagement with the ratchet teeth while the flywheel turns subsequent to return of the transerrer arm to normal position. The energy stored in the flywheel by the transerrer arm is dissipated during a period continuing from transfer until after the thread has been cut at the selvage, and when dissipating its energy the flywheel acts as a controller for the motor 45 and effects its energization for the purpose of removing the thread.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having bobbin transfer mechanism and in which a thread is to be removed from the loom when cut at the selvage several picks after operation of the transfer mechanism, a flywheel mounted for rotation, means to impart a rotary impulse to the flywheel upon each operation of the transfer mechanism and cause said flywheel to continue rotating for an interval until after the thread is cut at the selvage, thread removing mechanism for the thread, and means controlled by the flywheel and dependent upon rotation thereof during said interval to effect operation of the removing mechanism to remove said thread.

2. In a weft replenishing loom having bobbin transfer mechanism and in which a thread is to be removed from the loom when cut at the selvage several picks after operation of the transfer mechanism, a flywheel mounted for rotation, means to impart a rotating impulse to the flywheel whenever the transfer mechanism has an operation, said flywheel continuing to rotate sub-

sequent to operation of the transfer mechanism for an interval continuing until after the thread is cut at the selvage, thread removing mechanism for the thread, an actuator for the removing mechanism, and means controlled by the flywheel and operative due to rotation thereof during said interval to cause said actuator to operate the thread removing mechanism for the removal of said thread.

3. In a weft replenishing loom having bobbin transfer mechanism and in which a thread is to be removed from the loom when cut at the selvage several picks after operation of the transfer mechanism, a normally stationary flywheel, operating means causing rotation of the flywheel by a force derived from the transfer mechanism for an interval starting with operation of the transfer mechanism and continuing until after the thread is cut at the selvage, thread removing mechanism tending when actuated to remove said thread, an actuator for the thread removing mechanism, and means caused by said flywheel due to rotation thereof during said interval to cause the actuator to actuate the thread removing mechanism.

4. In a weft replenishing loom having bobbin transfer mechanism and in which a thread is to be removed from the loom when cut at the selvage several picks after operation of the transfer mechanism, a normally stationary flywheel set in rotation by a force derived from the transfer mechanism when the latter has a bobbin transferring operation and continuing to rotate until after the thread is cut at the selvage, thread removing mechanism for said thread, and means controlled by the flywheel and operative due to rotation thereof to effect operation of the thread removing mechanism and cause the latter to remove said thread.

5. In a weft replenishing loom having bobbin transfer mechanism and in which a thread is to be removed from the loom when cut at the selvage several picks after operation of the transfer mechanism, a normally stationary flywheel set in rotation by a force derived from the transfer mechanism when the latter has a bobbin transferring operation and continuing to rotate for an interval until after the thread is cut at the selvage, thread removing mechanism for said thread, an electric motor effective when energized to operate said thread removing mechanism, a normally open circuit operative when closed to energize said motor, and means dependent upon rotation of said flywheel during said period to close said circuit.

6. In a weft replenishing loom having bobbin transfer mechanism and in which a thread is to be removed from the loom when cut at the selvage several picks after operation of the transfer mechanism, a normally stationary flywheel set in rotation by a force derived from the transfer mechanism when the latter has a bobbin transferring operation and continuing to rotate for an interval until after the thread is cut at the selvage, thread removing mechanism for said thread, an electric motor effective when energized to operate said thread removing mechanism, a normally open electric circuit operative when closed to energize said motor, and normally open centrifugal electric switch means operatively connected to said flywheel and closed due to rotation of the latter during said interval and when closed causing closure of said electric circuit.

7. In a weft replenishing loom having bobbin transfer mechanism and in which a thread is

to be removed from the loom when cut at the selvage several picks after operation of the transfer mechanism, a normally stationary flywheel mounted for rotation, normally open centrifugal switch means mounted on said flywheel and caused to close by rotation thereof, thread removing mechanism for the thread, means to cause rotation of the flywheel incident to each replenishing operation of the loom for an interval continuing until after the thread is cut at the selvage, an electric motor which when energized operates the thread removing mechanism, and electric means controlled by said switch means and caused by the latter during said interval to energize said motor to cause operation of the thread removing mechanism.

8. In a weft replenishing loom having bobbin transfer mechanism and in which a thread is to be removed from the loom when cut at the selvage several picks after operation of the transfer mechanism, a rotatably mounted flywheel, ratchet teeth rigid with respect to and rotating with the flywheel, a pawl for the ratchet teeth, means connected to the transfer mechanism causing the pawl to operate the ratchet teeth to turn the flywheel when the transfer mechanism operates and cause said flywheel to continue to rotate for an interval continuing until after the thread is cut at the selvage, thread removing mechanism for the thread, actuator means for the thread removing mechanism, and means controlled by rotation of the flywheel during said interval causing said actuator means to operate said thread removing mechanism.

9. In a weft replenishing loom having bobbin transfer mechanism and in which a thread is to be removed from the loom when cut at the selvage several picks after operation of the transfer mechanism, a pawl and ratchet mechanism operated by the transfer mechanism whenever the latter operates, a flywheel set in rotation when said pawl and ratchet mechanism is operated by the transfer mechanism and rotating for an interval continuing until after the thread is cut at the selvage, thread removing mechanism for said thread, an electric motor effective when energized to operate said thread removing mechanism, centrifugal switch means normally open when the flywheel is at rest but closed due to rotation of the flywheel during said interval, and electric circuit means closed when said switch means is closed and causing energization of said motor.

10. In a weft replenishing loom having bobbin transfer mechanism and in which a thread is to be removed from the loom when cut at the selvage several picks after operation of the transfer mechanism, a normally stationary flywheel, ratchet means rigid with the flywheel and operative when actuated to cause rotation of the flywheel for an interval continuing until after the thread is cut at the selvage, a pawl connected to the transfer mechanism and out of engagement with the ratchet means when in normal position, the transfer mechanism when having an operation giving the pawl a working stroke, means operative at the start of said working stroke to move the pawl into engagement with said ratchet means and cause actuation of the latter to set the flywheel in rotation for said interval, thread removing mechanism tending when actuated to remove said thread, actuator means for said thread removing mechanism, and means caused by said flywheel due to rotation thereof during

said interval to cause the actuator means to actuate said thread removing mechanism.

11. In a weft replenishing loom having bobbin transfer mechanism and in which a thread is to be removed from the loom when cut at the selvage several picks after operation of the transfer mechanism, a normally stationary flywheel, ratchet means rigid with the flywheel and operative when actuated to cause rotation of the flywheel, a pawl which when in normal position is out of engagement with the ratchet means, means operative upon each operation of the transfer mechanism to give the pawl a working stroke and then return the pawl to normal position, means operative at the beginning of a working stroke of the pawl to move the latter into engagement with the ratchet means, whereupon the pawl acting through the ratchet means sets the flywheel in rotation, said rotation of the flywheel continuing after the pawl has returned to normal position and until after the thread is cut at the selvage, thread removing mechanism for said thread, and means controlled by the flywheel and operative due to rotation thereof to effect operation of said thread removing mechanism.

12. In a weft replenishing loom having bobbin transfer mechanism and in which a thread is to be removed from the loom when cut at the selvage several picks after operation of the transfer mechanism, a flywheel mounted for rotation, driving means operative incident to each operation of the transfer mechanism to impart a force to the flywheel causing rotation thereof for an interval continuing until after the thread is cut at the selvage and whether the flywheel be at rest or rotating due to a force previously imparted thereto by said driving means, removing mechanism for the thread, an actuator for the removing mechanism, and means controlled by the flywheel and dependent upon rotation thereof during said interval to cause said actuator to operate the removing mechanism.

13. In a weft replenishing loom provided with bobbin transfer means capable of having two successive bobbin transfer operations the first of which occurs at the beginning of a thread removing interval lasting for a given number of successive picks of the loom and the second of which occurs during said interval and at the beginning of a second thread removing interval similar in duration to the first interval and continuing after the latter, the loom having two threads to be removed, one remaining after the first transfer operation and the other remaining after the second transfer operation, and each thread being cut at the selvage prior to the end of the corresponding interval, a thread remover for said threads, actuator mechanism for said remover normally ineffective to cause said remover to remove said threads, and control means operated by the transfer means whenever the latter operates and continuing to operate for a period equal at least to said interval after each transfer operation and causing the actuator mechanism to operate said thread remover from the beginning of the first interval until the end of the second interval to remove both of said threads.

14. In a weft replenishing loom provided with bobbin transfer means capable of having two successive transfer operations the first of which occurs at the beginning of a thread removing interval lasting for a given number of successive picks of the loom and the second of which starts during said interval and at the beginning of a second thread removing interval similar in dura-

tion to the first interval and continuing after the latter, the loom having two threads to be removed, one remaining after the first transfer operation and being cut at the selvage during the first interval and the other remaining after the second transfer operation and being cut at the selvage during the second interval, a thread remover for said threads, actuator mechanism for said remover normally ineffective to cause said remover to remove said threads, and control means for said actuator mechanism receiving an impulse from the transfer means when the latter first operates causing operation of said control means for the first interval and receiving a second impulse from the transfer means when the latter operates the second time during said first interval and causing continued operation of the control means for the second interval, said control means causing the actuator mechanism to operate the thread remover from the beginning of the first interval until the end of the second interval to remove both of said threads.

15. In a weft replenishing loom having bobbin transfer means capable of having two successive transfer operations and in which two threads to be removed remain after said operations, one thread remaining after each transfer operation, each thread being cut at the selvage a given number of picks of the loom after the corresponding transfer operation, and the second operation of the transfer means occurring before cutting of the thread corresponding to the first transfer operation, removing mechanism for said threads, actuating mechanism for said removing mechanism normally ineffective to cause the latter to remove said threads, and control means for said actuating mechanism operated by the transfer means whenever the latter operates and effective when the latter first operates to cause said actuator mechanism to operate said removing mechanism for an interval of control starting with the first transfer operation and continuing after cutting at the selvage of the thread corresponding to said first transfer operation, said control means operative upon the second transfer operation which occurs prior to said cutting corresponding to the first transfer operation to start a second interval of control and causing the actuating mechanism to continue operation of the thread removing mechanism until after cutting at the selvage of the thread corresponding to the second transfer operation.

16. In a weft replenishing loom having bobbin transfer mechanism operating on replenishing picks of the loom and in which a thread to be removed from the loom remains after each replenishing pick and is subsequently cut at the selvage, a thread remover, actuator mechanism for said remover normally ineffective to cause said remover to remove the thread, movable control means which whenever given an actuating impulse on any replenishing pick of the loom causes said actuator mechanism to operate the thread remover during an interval of a given number of successive picks starting with the replenishing pick and continuing after cutting of the thread corresponding to the replenishing pick, said interval being long enough to enable said remover to remove said thread, and means operated by said transfer mechanism whenever the latter has a transfer operation to give said control means an actuating impulse whether or not said transfer operation occurs during an interval similar to the aforesaid interval but corresponding to the previous replenishing pick.

17. In a weft replenishing loom having bobbin transfer mechanism and in which a thread to be removed from the loom remains after an operation of the transfer mechanism and is cut at the selvage several picks of the loom after said operation, movable means having motion imparted thereto and having energy stored therein due to operation of the transfer mechanism, said means continuing to move after operation of the transfer mechanism and dissipating the energy stored 10

therein during an interval starting with the operation of said transfer mechanism and continuing until after the thread is cut at the selvage, thread removing mechanism tending when actuated to remove said thread, and control means for said removing mechanism operated by said movable means and operative during said interval to effect actuation of said thread removing mechanism.

ALBERT CEDERLUND.
